UNITED STATES PATENT OFFICE.

GOSTWYCKE MARSHALL, OF NAMPA, IDAHO, ASSIGNOR OF ONE-TENTH TO EDWARD M. GOODRICH, OF BOISE, IDAHO.

HORSESHOE.

No. 923,060.

Specification of Letters Patent. Patented May 25, 1908.

Application filed August 10, 1908. Serial No. 447,809.

To all whom it may concern:

Be it known that I, GOSTWYCKE MARSHALL, a citizen of the United States, residing at Nampa, Idaho, have invented certain new and useful Improvements in Horse-shoes, of which the following is a specification.

My invention relates to horse-shoes and is designed to furnish a shoe with an elastic heel for use on hard roads and paved streets to absorb the concussion and thus protect the hoofs.

Spring supported calks have heretofore been proposed, but it is the aim of my invention to provide a specially constructed device which shall be supported so as to be durable and of such a construction as will be self-cleaning, preventing the filling up of the parts with dirt which in so many constructions as heretofore proposed renders the action of the springs negligible.

In the accompanying drawing:—Figure 1 shows a side elevation of a shoe embodying my improvements. Fig. 2 is a plan view 25 with the spring calk removed on one side. Fig. 3 is a sectional view through one of the spring calks and its supporting base. Fig. 4 is a detail section.

In these figures the shoe proper is shown at A and may be of any suitable construction. At the heels or terminals of the shoe I round and incline the ends as at a and immediately in rear of the rounded part of the shoe I cut away the metal leaving a central ridge b with inclined portions c. The spring heel or calk is shown at C and is preferably riveted to the body of the shoe as shown in Fig. 2 as I prefer this method of joining the parts to welding as the weld is sure to break. The heel is made of spring metal and is bent so as to bridge the ridge b and has an upwardly extending half round portion e, which engages and bears upon the rounded end of the shoe proper.

The calk projects from the lower surface 45 as at f at about the center of the arch. It

will thus be seen that the spring heel is not only supported where it is joined to the shoe proper, but it is also fully supported at its extreme outer end and has a bearing in the up and down movement on the rounded end of the shoe to which the end of the heel corresponds and which it partially incloses. The up and down movement keeps the parts free from dirt and gives a bearing in all positions of the spring heel. As the full weight of the horse comes upon the heel it is not only depressed, but lengthened and finds a bearing at the base or upper end of the inclined end of the shoe, and as the pressure is taken off, as in the lifting of the hoof, the spring exerts itself and is separated from the shoe proper slightly and in the natural shortening of the spring it finds a bearing toward the lower end of the inclined wall of the shoe. The construction of the cut-away portion is such as to prevent any accumulation of dirt at this point as the up and down movement of the spring part in connection with the ridge and the inclined cut-away parts will keep everything clear at this point and thus there is nothing to interfere with the perfect action of the spring.

What I claim is:—

1. In a horse shoe, a spring heel or calk, having a permanent support at one end; an upwardly inclined laterally rounded support for its opposite end, the spring part corresponding to its support and inclosing the same, substantially as described.

2. A horse shoe having rounded inclined ends combined with a spring heel or calk having a tread intermediate of its ends, its free end conforming to the end of the shoe and covering the same, substantially as described.

In testimony whereof, I affix my signature in presence of two witnesses.

GOSTWYCKE MARSHALL.
